UNITED STATES PATENT OFFICE

DAVID C. KLAUSMEYER, OF CINCINNATI, OHIO, ASSIGNOR TO THE CINCINNATI BICK-FORD TOOL COMPANY, OF OAKLEY, CINCINNATI, OHIO, A CORPORATION OF OHIO

SPINDLE COUNTERBALANCE

Application filed October 24, 1924. Serial No. 745,671.

This invention relates to drilling-machines and it deals primarily with the means for counterbalancing the weight of the spindle and its associated elements whereby the 5 spindle may readily be moved up and down for the purpose of feeding the drill into and out of the work; all while permitting the spindle to rotate.

Heretofore, it has been usual to employ 10 a weight for the purpose of counterbalancing the spindle and it has, accordingly, been necessary to provide space in or adjacent the frame of the machine to accommodate the movement of the weight. Furthermore, when a weight is employed it has 15 to be of suitable proportions and means must be provided for so that the path of the weight will not be in the immediate proximity of the spindle; all of which has entailed some structural objections. Still further the employment 20 of a weight does not make it possible easily to adjust the degree of the counterpull on the spindle to meet any particular circumstances of use.

In an effort to overcome the various disadvantages inherent in the weight type of counterbalance and the inconveniences in the installation, use and adjustment thereof several spring counterbalance devices have heretofore been designed. These latter devices, which, in certain respects, have been a 25 decided improvement over the weight type of counterbalance have, nevertheless, also embodied certain structural objections which have prevented them from being entirely satisfactory and which this invention proposes to cure.

This invention has for an object to provide an improved form of spring counterbalance for drilling machines which is exceedingly simple in construction; which may be more readily assembled and dismantled than prior constructions and which permits of ready removal of the normally inaccessible 45 drill-spindle from the drill-head. A further object of the invention is to provide, in a spring type counterbalance, means to control the spring and to prevent unnecessary unwinding thereof upon failure of the chain 50 connecting the spindle with the counter-

balance. Another object of the invention is to provide an auxiliary stop for the rotary element upon which the chain is wound whereby the parts may be brought to rest in a position in which the connection between 55 the counterbalance and the drill-spindle is accessible through a suitable aperture formed in the drill-head whereby the spindle may be disconnected from the counterbalance and readily removed from the drill-head. A still 60 further object of the invention is to provide in a spring counterbalance simplified means for regulating the tension of the spring and for holding it under any desired degree of tension.

Other objects and advantages will be in part indicated in the following description and in part rendered apparent therefrom in connection with the annexed drawings.

To enable others skilled in the art so fully 70 to apprehend the underlying features hereof that they may embody the same in the various ways contemplated by this invention, drawings depicting a preferred typical construction have been annexed as a part of this 75 disclosure and, in such drawings, like characters of reference denote corresponding parts throughout all the views, of which:—

Fig. 1 is an elevation of a portion of a drilling machine embodying the present invention. Fig. 2 is a horizontal section substantially on the line 2—2 of Fig. 3. Fig. 3 is a view somewhat similar to Fig. 1 but having a portion of the casing broken away better to illustrate certain of the mechanism there- 85 beneath. Fig. 4 is a face view of the spring housing with the cover thereof broken away better to show the means for holding the opposite ends of the counterbalance spring. Fig. 5 is a detail view of a fusee employed in 90 the counterbalancing device. Fig. 6 is a detail side elevation of a portion of Fig. 1 showing particularly the means for attaching the spindle supporting chain with the spindle and the means for moving the spindle vertically in the head. Fig. 7 is a detail section through a portion of the spring housing and 95 the casing within which the housing is maintained, showing certain stop-lugs later to be referred to. Fig. 8 is a view similar to Fig. 100

7 but showing the function of an auxiliary stop for the spring casing.

Referring more particularly to the drawings the invention is disclosed in its preferred form as embodied in a drill-head of which a portion is designated as 1. This head is of conventional form and is provided with the usual vertical hole 2 within which is vertically shiftable a sleeve 3 forming a part of the drill-spindle unit. This sleeve does not rotate but it may be translated by means of a pinion 4 engaging with the teeth t of a rack-bar 5 affixed to one side of the sleeve. The pinion 4 is carried by a shaft 6 journaled in the head and this shaft may be rotated by any suitable means to cause vertical movements of the sleeve 3. Within the sleeve is rotatably journaled the usual drill-supporting spindle 7 which may be rotated by any suitable means common to drilling machines. The drill-spindle is maintained against endwise movement relative to the sleeve and therefore partakes of the vertical movements of the latter.

The weight of the sleeve 3, spindle 7 and their attached parts is sustained, without interfering with their vertical movements, by an improved form of spring counterbalance device maintained within a casing 8 carried by the drill-head 1. A link chain 9, having one end connected with the sleeve and the opposite end connected with the counterbalance affords convenient means for transmitting the weight of the former to the latter. The attachment of the chain to the sleeve may be effected by means of a block 10 secured by screw 10^a to the rack-bar 5 and to which the chain is connected, as at 11. It is to be noted that the teeth t of the rack-bar terminate adjacent the lower end of the block 10 and therefore when the block is removed, as will later be described, rotation of the pinion 4 in one direction will cause complete disengagement of rack and pinion and the sleeve and spindle may be withdrawn from the drill-head as a unit.

To the casing 8 is secured, as by screws 12, a cover 13 formed with a bearing 14 for a short shaft 15 upon which is rotatably journaled a housing 16. The shaft 15 is normally held against rotation in the bearing 14 by set screws 15^a and 15^b threaded through the walls of the bearing and which bear upon flattened surfaces 15^c and 15^d respectively formed on the shaft 15. The screws 15^a and 15^b preferably engage the surfaces 15^c and 15^d above and below a horizontal plane passing through the axis of the shaft, better to receive and withstand the torsional strains to which the shaft is subjected. Within the housing 16 is held a spiral spring 17 of which one end is secured to the shaft 15 by a pin 18. The other end of the spring is formed as a hook 19 which engages the wall 20 of a slot 21 in the peripheral wall of the housing 16. The

housing 16 carries at its rear side a member 22 in the nature of a fusee on the periphery of which winds the chain 9. The periphery of the fusee provides a shallow groove 23 and this groove is of spiral formation so that it progressively increases in distance from the axis of rotation of the fusee. The chain is attached at one end to the fusee at a point most remote from its axis of rotation as by means of its connection with a block 24 held by a screw 25 in a slot 26 formed in the fusee. 75

It will be perceived that, in consequence of this arrangement, as the spindle is lowered, and as the spiral spring 17 increases in tension, the point at which the chain leaves the fusee will be more and more remote from the axis of rotation; in other words the leverage effect of the fusee on the spring increases as the tension of the spring increases, and conversely. In this manner the chain 9 is subjected to a constant tension in all positions of the spindle although the spiral spring has its tension increased as it becomes wound more and more tightly. 80

It sometimes happens in both spring and weight counterbalances that the cable or chain connecting the spindle with the counterbalance breaks under the strains to which it is subjected. In the spring type of counterbalance this breakage is immediately followed by rapid and complete unwinding of the counterbalance spring which not infrequently damages the spring or other parts of the counterbalance. Also unwinding of the spring caused the chain to be drawn into the casing from which position it was difficult to be retrieved for a subsequent attachment to the drill-spindle. An important feature of this invention consists in the provision of a safety device adapted, upon failure of the chain to support the spindle, to limit the unwinding action of the spring and to bring the parts of the counterbalance to rest without injury thereto. This may conveniently be effected by forming on the cover 13 an abutment in the nature of a lug 27 located in the annular path of a similar abutment 28 carried by the rotatable housing 16. For convenience of manufacture the lug 28 may be formed integral with a cover-plate 29 fitted within an annular recess 30 in the housing and held therein as by means of screws 31. The lugs 27 and 28 are so arranged that during the normal operation of the machine the housing 16 and the fusee carried thereby are permitted to receive almost a complete rotation before the surface 28^a of the lug 28 contacts with the surface 27^a of the lug 27 thereby stopping the downward movement of the drill-spindle. This extent of rotation of the parts permits the drill-spindle to be given vertical movements of sufficient amplitude to perform the drilling operations. Upon failure of the chain, which causes the 95

spring 17 to be relieved of the weight of the spindle and its associated elements, the spring unwinds thereby rotating the housing 16 until the surface 28^b of the lug 28 is brought 5 into contact with the surface 27^b of the lug 27. This contact arrests the rotation of the parts and prevents unnecessary unwinding of the spring.

Upon failure of the spindle to be supported, unless some special means was provided the spindle would fall of its own weight clear of the drill-head which falling might readily injure the workman, the work or the spindle. This is prevented in the present machine by locating the block 10 at the upper end of the rack-bar in which place it acts as a stop against the pinion 4 and prevents falling of the spindle.

It occasionally happens that it is necessary 20 to remove the drill-spindle unit from the drill-head. In prior machines this has entailed quite some difficulties first because the connection between spindle and the chain was usually more or less inaccessible and second 25 it was necessary, both when disconnecting the spindle from the chain and also when renewing this connection, to overcome the pull of the counterbalance. In weight counterbalances this was sometimes effected by prop- 30 ping up the weight and in the spring counterbalance this could most conveniently be effected by completely unwinding the spring and thereby relieving it of all tension. These 35 expedients were dangerous, bothersome and wholly unsatisfactory.

The present invention overcomes this difficulty in a very simple and ingenious manner now to be described. The casing, or preferably the cover 13 thereof carries a normally ineffective abutment adapted, at any desired 40 time to be brought into the path of another abutment carried by the rotatable housing 16, thus by a suitable adjustment of one of the abutments the rotatable housing, the 45 spring therein, and the fusee carried thereby may all be brought to rest thereby relieving the chain of the counterpull of the spring. One convenient means for effecting this result 50 comprises a screw 32 threaded into the casing 13 and having an end 32^x adapted to be brought into the path of the lug 28 whereby upon elevation of the spindle the lug will engage the screw and bring both the rotatable member and the spindle to rest in a pre- 55 determined position with the spring ineffective to exert a counterpull on the chain. The lug 28 and the screw 32 are so arranged that when they are in contact the screw 10^x that 60 secures the block 10 to the spindle is in view and readily accessible through an orifice 33 in the drill-head (see Fig. 3). It will be understood that with the parts in these positions the screw 10^x may readily be taken out, thus disconnecting the block 10 from the 65 rack-bar 5 and permitting the spindle to be

dropped clear of the pinion 4 and the drill-head, without any movement of the parts of the counterbalance. Fig. 8 shows the screw 32 adjusted to its effective position and Fig. 7 shows it maintained out of the path of the lug 70 28 as by means of a spacer-nut 34, the same being provided to prevent accidental or unauthorized shifting of the screw into the path of the lug.

When, for any reason, it is desired to 75 change the tension of the spring 17 this may readily be done by applying a suitable wrench to the squared end 15^x of the shaft 15, loosening the set-screws 15^a and 15^b and then, by means of the wrench, rotating the shaft until the desired tension is secured, after which the screws 15^a and 15^b may again be adjusted 80 into contact with the flats 15^c and 15^d to hold the parts in their adjusted positions.

From the foregoing it will be perceived 85 that I have provided an exceedingly simple, compact, inexpensive and efficient counterbalance embodying means for controlling the action of the counterbalance spring, means to permit of ready removal of the spindle from the drill-head, and means to provide for the 90 necessary adjustment of the counterbalance spring.

Without further analysis, the foregoing 95 will so fully reveal the gist of this invention that others can, by applying current knowledge, readily adapt it for various utilizations by retaining one or more of the features that, from the standpoint of the prior art, fairly constitute essential characteristics of either 100 the generic or specific aspects of this invention and, therefore, such adaptations should be, and are intended to be, comprehended within the meaning and range of equivalency of the following claims.

Having thus revealed this invention, I 105 claim as new and desire to secure the following combinations and elements, or equivalents thereof, by Letters Patent of the United States:—

1. A drilling machine combining a drill-spindle, and a spring counterbalance therefor comprising a rotatable member; a flexible connection between said rotatable member and said drill-spindle for transmitting to the former the weight of the latter; a spring connected with said rotatable member and adapted to exert a counterpull on said flexible connection; and means to limit the rotation of said rotatable member whereby the spring 115 cannot fully unwind upon being released from the weight of said drill spindle.

2. A drilling machine combining a drill-spindle, and a spring counterbalance therefor comprising a rotatable member; a flexible 120 connection between said rotatable member and said drill-spindle for transmitting to the former the weight of the latter; a spring connected with said rotatable member and adapted to exert a counterpull on said flexible con- 125

nection; and means acting directly upon said rotatable member to limit its rotation to less than the range of said spring.

3. A drilling machine combining a drill-spindle, and a spring counterbalance therefor comprising a rotatable member; a flexible connection between said rotatable member and said drill-spindle for transmitting to the former the weight of the latter; a spring connected with said rotatable member and adapted to exert a counterpull on said flexible connection; an abutment carried by said rotatable member; and means cooperating with said abutment to limit the rotation of said rotatable member.

4. A drilling machine combining a drill-spindle, and a spring counterbalance therefor comprising a rotatable member; a flexible connection between said rotatable member and said drill-spindle for transmitting to the former the weight of the latter; a spring connected with said rotatable member and adapted to exert a counterpull on said flexible connection; and means operative upon failure of the flexible connection to limit the unwinding of the spring.

5. A drilling machine combining a drill-spindle and a spring counterbalance therefor comprising a casing supported by the drill-head; a member rotatably mounted in said casing; a fusee carried by said rotatable member; a flexible connection between said fusee and the spindle; a spring having one end connected with said rotatable member and adapted to exert a counterpull on said flexible connection to support the weight of said spindle; and an abutment carried by said casing and maintained in the path of movement of a portion of said rotatable member to limit the rotary movement of said rotatable member.

6. A drilling machine combining a drill-spindle, and a spring counterbalance therefor comprising a rotatable member; a flexible connection between said rotatable member and said drill-spindle for transmitting to the former the weight of the latter; a spring connected with said rotatable member and adapted to exert a counterpull on said flexible connection; and means located in the path of rotation of said rotatable member to limit its movement to less than a complete rotation.

7. A drilling machine combining a drill-spindle and a spring counterbalance therefor comprising a rotatable member; a flexible connection between said rotatable member and the spindle; a spring operatively connected with said rotatable member; means to limit the rotation of said rotatable member; and an auxiliary means to arrest the rotation of said rotatable member intermediate its extreme positions of rotation.

8. In a drilling machine, a drill-spindle and a counterbalance device for said drill-spindle, said counterbalance comprising a casing; a shaft journaled in said casing; a

housing rotatably mounted in said casing; a spiral spring located in said housing and operatively connecting said housing and said shaft; a fusee carried by said housing; a flexible connector secured at its opposite ends to said spindle and to said fusee and adapted to be wound upon the latter; a lug carried by said rotatable housing; a lug carried by said casing in the path of movement of said first named lug to limit the rotary movements of said housing; and auxiliary means adapted to be placed in the path of movement of said first named lug to arrest the rotation of the parts before said parts reach their normal stopping positions.

9. A drilling machine combining a drill-head provided with an orifice; a spindle translatablely mounted in said drill-head; a spring counterbalance for said spindle, said counterbalance including a rotatable member, a flexible connector adapted to be wound upon said rotatable member; means to attach one end of said flexible connector with said spindle; and means to arrest the rotation of said rotatable member with said chain attaching means adjacent said orifice to permit of detachment of said chain from said spindle.

10. In a drilling machine, a drill head provided with an orifice; a spindle translatablely mounted in said drill-head; means to cause translation of said spindle in said drill-head; a counterbalance for said spindle, said counterbalance including a rotatable member, a flexible connector attached at one end to said spindle and adapted to be wound upon said rotatable member as said spindle is elevated; and means to render said counterbalance ineffective to produce a counterpull on said spindle when the spindle is in a predetermined position with respect to said orifice.

11. In a drilling machine, a drill-head provided with an orifice; a spindle translatablely mounted in said drill head; a rack-bar carried by said spindle; a pinion rotatably journaled in said drill-head and meshing with said rack-bar; a counterbalance device for said spindle; a flexible connector adapted to receive the counterpull of said counterbalance; means to attach one end of said connector with said spindle, said means including an attachment block located adjacent the end of said rack-bar and forming an abutment to prevent disengagement of the rack and pinion; a screw securing said attachment block to said spindle; and a movable abutment adapted to be brought into the path of movement of a portion of said counterbalance to render said counterbalance ineffective and said connector strain-free in a position wherein said screw is accessible through said orifice.

12. A drilling machine combining a drill-spindle and a counterbalance therefor, comprising a casing; a shaft rotatably journaled

in said casing; a housing rotatably mounted on said shaft; a spiral spring within said housing and having one end connected with the housing and the other end secured to said shaft; a fusee secured to said housing; a flexible connector having one end secured to the fusee and the other end attached to said drill spindle; means for applying power to the shaft to change the tension of said spring; means carried by said casing and adapted to engage said shaft to hold it against rotary movement in its adjusted position; and an abutment carried by said rotatable housing, and two abutments carried by said casing one of which is adjustable, said abutments being adapted to bring said rotatable housing to rest in either of two positions.

13. A drilling machine combining a drill-spindle and a counterbalance therefor comprising a casing; a shaft rotatably journaled in said casing; a housing rotatably mounted on said shaft; a spiral spring within said housing and having one end connected with the housing and the other end secured to said shaft; a fusee secured to said housing; a flexible connector having one end secured to the fusee and the other end attached to said drill spindle; means for applying power directly to the shaft to change the tension of said spring; and set screws threaded through said casing engaging flattened portions of the shaft at opposite sides thereof and at opposite sides of a plane passing through the axis of the shaft.

35 In witness whereof, I have hereunto subscribed my name.

DAVID C. KLAUSMEYER.
